INK FOUNTAIN

Original Filed July 7, 1926 2 Sheets-Sheet 2

UNITED STATES PATENT OFFICE

HANS C. SCHROEDER, OF LA GRANGE, ILLINOIS, ASSIGNOR TO GOSS PRINTING PRESS COMPANY, A CORPORATION OF ILLINOIS

INK FOUNTAIN

Original application filed July 7, 1926, Serial No. 120,909. Divided and this application filed August 9, 1927. Serial No. 211,715.

My invention relates to printing presses and more particularly to the ink fountains employed in printing presses, and to means for keeping the pigment of the ink uniformly distributed throughout the body of the ink in the fountain while using any particular kind of ink under any particular set of operating conditions. My invention further relates to automatically agitating all the ink in 10 the fountain while the press is running.

This application is a division of my pending application, Ser. No. 120,909, filed July 7th, 1926.

Objects and advantages will be set forth 15 in part hereinafter and in part will be obvious herefrom, or may be learned by practice with the invention, the same being realized and attained by means of the instrumentalities and combinations pointed out in the 20 appended claims.

The invention consists in the novel parts, constructions, arrangements, combinations, improvements and method herein shown and described.

25 The accompanying drawings, referred to herein and constituting a part hereof, illustrate one embodiment of the invention, and together with the description, serve to explain the principles of the invention.

30 Of the drawings:—

Fig. 1 is a vertical section along line 1—1 of Fig. 3, through an ink fountain of the overshot type, equipped with one form of my invention;

35 Fig. 2 is a fragmentary vertical section on line 2—2 of Fig. 1;

Fig. 3 is a plan view, partly broken away, of the fountain shown in Fig. 1.

To more readily distinguish my invention 40 from other inventions, and to comply with Section 4888 of the Revised Statutes, I shall briefly refer to the form of ink fountain which is now commonly employed in printing presses.

45 The usual type of ink fountain for a printing press is provided with a rotatable fountain roller which rotates a portion of its surface in contact with the ink in the fountain at all times, so as to accumulate ink to be transferred to the doctor roll. At the point where

the rotating surface of the roller emerges from the fountain there is positioned a doctor blade which serves to scrape the surplus ink from the surface of the roller. As the fountain roller rotates, it sets up a local convection current or eddy in the ink adjacent to its surface. This convection current travels with the surface of the roller to the point of junction of the roller with the doctor blade. Since a relatively small amount of ink is allowed to pass to the edge of the doctor blade, the convection current is rebuffed or turned away from the surface of the roller and travels in a reverse direction on a course slightly divergent from the surface of the roller for a certain distance, when it completes its circuit by being drawn back to the rotating roller surface. Thus there is set up in the ink a local convection current which, however, fails to effect the great mass of ink in the 70 fountain removed from the roller and which, therefore, is left dead or unagitated. After the press has been running for a comparatively short time it is found in practice that the pigment is withdrawn or used up from the 75 local current of ink described above and consequently the ink which is picked up by the fountain roller becomes thin and loses color. Under the present practice, when this condition arises, the doctor blade has to be somewhat further separated from the fountain roller in order to obtain sufficient color from the thin ink which is being fed from the local currents. Again, in the present practice, when the press is idle there is, of course, no 80 local convection current, so that the pigment throughout the body of the ink tends to settle to the bottom of the fountain, thus causing an uneven distribution and mixture of the pigment with the ink and making it necessary to stir up the ink by hand or other means in order to secure a proper mixture. Ordinarily in running color, it is necessary for the pressman to stir up the ink in the fountain by hand about every 15 minutes.

By my invention I eliminate all these objectionable features and insure that the pigment in the ink will be uniformly and automatically distributed throughout the ink in the fountain. It will not be necessary to adjust the 100

doctor blade to permit an additional quantity of thin ink to be taken up by the fountain roller, for by use of the invention, the coloring content and the consistency of the ink will always be uniform, insuring uniformity of color in the printed product. Further, any tendency that the pigment has to settle out by gravity will automatically be corrected by currents of ink set up in the fountain.

10 My present invention is directed to a novel method of causing the local convection currents set up in the vicinity of the fountain roller of the ink fountain of a printing press to diverge from their natural 15 paths and flow through the mass of ink in the fountain which is removed from the fountain roller in such a way as to thoroughly agitate said ink and set up and maintain an even distribution of the pigment therein.

20 My present invention is also directed to means for directing the flow of the above mentioned convection currents throughout the mass of ink in the fountain so as to obtain and maintain the most desirable mixture 25 of the pigment or coloring matter in the ink. The invention is further directed to effecting and maintaining the desired color and consistency of ink in the fountain 30 by a method which requires the introduction of no forces other than those employed in the actual operation of an ordinary ink fountain.

35 My present invention is adapted to carry out the novel method described above for agitating and maintaining the proper mixture and distribution of ink in the ink fountain with any particular kind of ink used under any particular set of operating conditions which may vary the ink used.

40 My present invention is adapted to carry out the novel method described above for agitating and maintaining the proper mixture and distribution of ink in the ink fountain with any particular kind of ink used under any particular set of operating conditions which may vary the nature of the ink used.

45 As more fully set forth and shown in my copending applications Ser. No. 211,712 Ser. No. 211,713 Ser. No. 211,714 filed as of even date herewith, the presence of a suitably positioned baffle plate in an ink fountain of a printing press will deflect from 50 the local convection currents set up by the rotation of the fountain roller through the ink, away from the vicinity of the fountain roller and throughout the mass of ink in the fountain, with the result that the pigment 55 of said ink will be maintained in the proper proportion throughout the entire mass of ink. In other words, the proper direction and control of the convection currents will insure a thorough circulation and agitation 60 of all the ink in the fountain with the at-

tendant beneficial effects on the printing qualities of the ink. The flow of the ink and the convection currents set up by the movements of the fountain roller depend to a great extent upon the character of the 70 particular ink used, the temperature at a given time, and a number of other conditions. It is therefore highly desirable to be able to vary the position of the baffle plate to meet these conditions and to direct the 75 convection currents of ink so as to obtain the most efficient and constant mixture, consistency, and coloring of the ink. Experience has shown that for certain kinds of ink used under particular conditions of operations, the best results are obtained when the baffle plate is of curved or approximately curved surface, the direction and amplitude of curvature depending upon a given 80 set of conditions of operation and the particular ink used.

85 Referring now to the embodiment of the invention, illustrated by way of example in the accompanying drawings 21 (Fig. 1) is a standard form of ink fountain for a printing 90 press equipped with the ordinary form of overshot fountain roller 22, co-operating with the usual doctor roll, (not shown). This fountain 21 is provided with the ordinary form of doctor blade 23 supported in 95 any suitable manner at 23^a, all as in the usual practice.

90 Means for deflecting the convection currents set up by the rotation of the fountain roller 22, which rotates in the direction indicated by the arrow, are provided for carrying out the method of my invention. A multi-part baffle plate comprising the forward section 65 and the rear or heel section 66, is secured to the brackets 51, 51^a by rivets 100 or any other suitable fastening means. The bracket 51 is keyed to a rod 53, (Fig. 2), the ends of which are loosely journaled in the downwardly extending arms 156, which extends across the fountain and to the opposite 105 end of which is keyed a similarly arranged supporting means for the baffle plate. Since the supporting and variable positioning mechanism for baffle plate consists of duplicate sets, one at each side of the fountain 110 21, only one of these sets will be described. Pinned to the rod 53 by the pin 55 is the upwardly extending arm 54. The bracket 51^a 115 is a horizontal extension of arm 156. The arm 156 is pivoted on a stud 60, mounted in a slot 61 in the bracket 62, fast on the fountain 21. As shown in Fig. 1, the multi-part baffle plate 65, 66 is suspended in the fountain 21 so that the forward section 65 lies in a plane 120 substantially parallel to the bottom of the fountain 30 at a slight angle to the heel section 66, which lies in a substantially horizontal plane.

125 Means are provided for varying the position of the entire multi-part baffle plate 65,

66 so that it can be nicely and accurately set so as to best carry out its function of maintaining the proper mixture and distribution of ink in the fountain under any particular set of operating conditions. Refer-

5 ring primarily to the mounting of the arm 156, the stud 60 is maintained in position by means of the nut 63 (Fig. 2). It is readily apparent that by loosening the nut 63, arm 156 is vertically slidab'e within the limits of the slot 61, and means are thereby provided for varying the vertical position of the entire multi-part baffle plate within desirable limits in order to meet varying conditions of 10 operation. Further, the loosening of the nut 63 permits of an angular movement of the arm 156 about its pivot 60, whereby a further variation of the position of the entire baffle plate can be obtained.

20 Referring now to the arm 54, it will be seen that means are provided for independently changing the angular relation between the two sections of the multi-part baffle plate. The upper end of arm 54 is provided with 25 arcuate slot 57 through which extends a thumb screw 58 mounted on the arm 156. It is clear that by loosening the thumb screw 58 the angular inclination of the section 65 can be varied within the limits of the arcuate 30 slot 57, and by tightening the thumb screw 58 such angular inclination can be set and maintained.

It is clear by the use of the various combinations of the above described variable positioning means, the baffle plate can be set 35 in any position relative to the fountain roller, the doctor blade and the bottom of the fountain, which is desirable for the carrying out of its function under any possible set of 40 working conditions. Also by virtue of the last described means, it is possible to nicely position not only the whole baffle plate, but to change the form thereof to meet a given set of conditions, that is, the changing of 45 the angular relation between the two sections 65 and 66 gives the multi-part baffle plate the approximate form of a curved plate whose curvature can be changed at will within 50 desirable limits. For example, the ar- 55 rangement shown in Fig. 1 gives a baffle plate whose forward edge lies adjacent the surface of the rotating fountain roller and the general outline of which is that of a plate of upwardly convex curvature. It is readily 60 conceivable that by moving the section 65 through the angle determined by the slot 57 that a plate of downwardly convex curvature 65 will be obtained. Any desired curvature be- 65 tween these indicated limits is of course, as readily obtainable.

It is to be understood that my multi-part baffle plate is not limited to two or any particular number of sections, the two sections 65 shown in the present embodiment being so

shown merely for convenience of description and illustration.

What I claim is:—

1. An ink fountain for a printing press including in combination a fountain roller adapted to rotate therein, and means to determine the direction of the ink currents, throughout the fountain comprising a baffle plate formed of a plurality of sections. 70

2. An ink fountain for a printing press including in combination a fountain roller adapted to rotate therein, and variably positionable means to determine the direction of the ink current throughout the fountain comprising a baffle plate formed of a plurality of sections. 75

3. An ink fountain for a printing press including in combination a fountain roller adapted to rotate therein, and means to determine the direction of the ink currents throughout the fountain comprising a baffle plate formed of a plurality of sections, one of said sections being variably positionable 80 with respect to the others. 85

4. An ink fountain for a printing press including in combination a fountain roller adapted to rotate therein, and variably positionable means to determine the direction of the ink currents throughout the fountain comprising a baffle plate formed of a plurality of sections. 90

5. An ink fountain for a printing press including in combination a fountain roller adapted to rotate therein, and means to determine the direction of the ink current throughout the fountain comprising a baffle plate formed of a plurality of sections, one of said sections being variably positionable 95 with respect to the others. 100

6. An ink fountain for a printing press including in combination a fountain roller adapted to rotate therein, means to determine the direction of the ink current throughout the fountain comprising a baffle plate formed of a plurality of sections, and means to vary the horizontal position of said baffle plate to change the direction of the said current. 105

7. An ink fountain for a printing press including in combination a fountain roller adapted to rotate therein, means to determine the direction of the ink current throughout the fountain comprising a baffle plate formed of a plurality of sections, and means to vary the vertical position of said baffle plate to change the direction of said current. 115

8. An ink fountain for a printing press including in combination a fountain roller adapted to rotate therein, means to determine the direction of the ink current throughout the fountain comprising a baffle plate formed of a plurality of sections, and means to vary the angular inclination of said baffle plate to change the direction of said current. 125

9. An ink fountain for a printing press 130

including in combination a fountain roller adapted to rotate therein, means to determine the direction of the ink current throughout the fountain comprising a baffle plate formed of a plurality of sections, and means to vary the horizontal and vertical position of said baffle plate to change the direction of said current.

10. An ink fountain for a printing press including in combination a fountain roller adapted to rotate therein, means to determine the direction of the ink current throughout the fountain comprising a baffle plate formed of a plurality of sections and means to vary the horizontal and vertical position and the angular inclination of said baffle plate to change the direction of said current.

11. An ink fountain for a printing press including in combination a fountain roller adapted to rotate therein, means to determine the direction of the ink current throughout the fountain comprising a baffle plate formed of a plurality of sections, and means to vary the angular relation of said sections to give to said baffle plate the effect of a curved plate.

12. An ink fountain for a printing press including in combination a fountain roller adapted to rotate therein, means to determine the direction of the ink current throughout the fountain comprising a baffle plate formed of a plurality of sections, and means to vary the angular relation of said sections to approximate a curved plate of upwardly convex curvature.

13. An ink fountain for a printing press including in combination a fountain roller adapted to rotate therein, means to determine the direction of the ink current throughout the fountain comprising a baffle plate formed of a plurality of sections, and means to vary the angular relation of said sections to approximate a curved plate of downwardly convex curvature.

14. An ink fountain for a printing press including in combination a fountain roller adapted to rotate therein, means to determine the direction of the ink current throughout the fountain comprising a baffle plate formed of a plurality of sections, and means to vary the angular relation of said sections to give to said baffle plate the effect of a curved plate of any curvature between desired limits.

15. The combination in an ink fountain of a printing press of a fountain roller, and a baffle plate formed of a plurality of sections; said baffle plate being adapted to effect and maintain a uniform mixture of ink in the fountain.

16. The combination in an ink fountain of a printing press of a fountain roller mounted therein and a baffle plate formed of a plurality of sections, one section being variably positionable with relation to the other sections for the purpose of varying the direc-

tion of the convection currents of the ink in the fountain.

17. A baffle plate formed of a plurality of elongated members mounted on a common support and means for maintaining said members in variable angular relation.

In testimony whereof, I have signed my name to this specification.
